US00D847794S

(12) **United States Design Patent** (10) **Patent No.:** **US D847,794 S**
(45) **Date of Patent:** **** May 7, 2019**

(54) **EARPHONE**

(71) Applicant: **Mobvoi Information Technology Company Limited**, Beijing (CN)

(72) Inventors: **Shuai Guo**, Beijing (CN); **Jing Gu**, Beijing (CN); **Yang Liu**, Beijing (CN)

(73) Assignee: **Mobvoi Information Technology Company Limited**, Beijing (CN)

(**) Term: **15 Years**

(21) Appl. No.: **29/639,998**

(22) Filed: **Mar. 10, 2018**

(51) **LOC (11) Cl.** **14-01**

(52) **U.S. Cl.**

USPC **D14/223**

(58) **Field of Classification Search**

USPC D14/205, 221, 223, 224, 224.1, 225; D24/173, 174

CPC H04R 1/10; H04R 1/1016; H04R 1/1066; H04R 1/1033; H04R 1/08; H04R 5/033; H04R 5/0335; H04R 25/00

(57) **CLAIM**

The ornamental design for an earphone, as shown and described.

DESCRIPTION

FIG. 1 is a front plan view of an earphone showing the new design, showing the left earphone in a first embodiment;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front plan view of the earphone, showing the right earphone in a second embodiment;

FIG. 8 is a rear view thereof;

FIG. 9 is a left side view thereof;

FIG. 10 is a right side thereof;

FIG. 11 is a top view thereof; and,

FIG. 12 is a bottom view thereof.

The broken lines in the drawings depict portions of the earphone that form no part of the claimed design.

1 Claim, 4 Drawing Sheets
